CLAIM

The ornamental design for a single-head worklight stand, as shown and described.

DESCRIPTION

FIG. 1 is an overall perspective view of a first embodiment of single-head worklight stand showing my new design; FIG. 2 is a right elevational view of the worklight stand of FIG. 1, the left elevational view being a mirror image thereof;

FIG. 3 is a front elevational view thereof;

FIG. 4 is a rear elevational view thereof;

FIG. 5 is a top plan view thereof, wherein the broken line portion depicting the worklight head is omitted;

FIG. 6 is a bottom plan view thereof, wherein the broken line portion depicting the worklight head is omitted;

FIG. 7 is a right elevational view of a second embodiment of worklight stand, the left elevational view being a mirror image thereof;

FIG. 8 is a front elevational view thereof;

FIG. 9 is a rear elevational view thereof;

FIG. 10 is a top plan view thereof, wherein the broken line portion depicting the worklight head is omitted;

FIG. 11 is a bottom plan view thereof, wherein the broken line portion depicting the worklight head is omitted;

FIG. 12 is a front elevational view of a third embodiment of worklight stand;

FIG. 13 is a rear elevational view of the embodiment of FIG. 12;

FIG. 14 is a top plan view thereof, wherein the broken line portion depicting the worklight head is omitted; and,

FIG. 15 is a bottom plan view thereof, where the broken line portion depicting the worklight head is omitted.

The broken lines are shown for illustrative purposes only and form no part of the claimed design.
